UNITED STATES PATENT OFFICE.

FRANK E. PELTON, OF WILKINSBURG, AND JAMES RENWICK LOVE, OF ALLEGHENY, PENNSYLVANIA.

HEAD FOR BARRELS, CASKS, &c.

SPECIFICATION forming part of Letters Patent No. 635,583, dated October 24, 1899.

Application filed July 3, 1897. Serial No. 643,378. (No model.)

To all whom it may concern:

Be it known that we, FRANK E. PELTON, residing at Wilkinsburg, and JAMES RENWICK LOVE, residing at Allegheny, in the 5 county of Allegheny and State of Pennsylvania, citizens of the United States, have invented a new and useful Improvement in Heads for Barrels, Casks, &c.; and we do hereby declare the following to be a full, clear, 10 and exact description thereof.

Our invention relates to an improvement in heads for barrels, casks, &c.

The object of our invention is to provide a 15 head for barrels, casks, kegs, pails, packages, and other like articles which can be easily inserted within and removed from the article without disturbing the hoops or other fastenings thereof.

A further object of our invention is to provide 20 a head which will tighten itself in the article and take up any shrinkage of the parts composing the same; and a still further object of our invention is to provide a head which is capable of expansion, so as to insure 25 a tight adjustment of the head in the article at all times.

Our invention consists, generally stated, in the novel arrangement, combination, and construction of the various parts of the device, 30 as hereinafter more specifically set forth and described, and particularly pointed out in the claims.

To enable others skilled in the art to which our invention appertains to construct and 35 use the same, we will describe the same more fully, referring to the accompanying drawings, in which—

Figure 1 is a top view of a keg or cask, showing our invention applied thereto. Fig. 2 is 40 a like view showing the bung removed and the wedges moved back into the bung-hole. Fig. 3 is a cross-section on the line 3 3, Fig. 1. Fig. 4 is a cross-section on the line 4 4, Fig. 2. Fig. 5 is a top view of a large head, 45 showing our invention applied thereto in another form for barrels, hogsheads, &c. Figs. 6 and 7 are top views of kegs or casks, showing the double wedges applied to the heads thereof in another form. Figs. 8 and 9 are top views 50 of kegs or casks, showing the single wedge applied to the heads thereof; and Figs. 10,

11, 12, and 13 are perspective views of different forms or shapes of heads having our invention applied to the same for packages, &c.

Like letters herein indicate like parts in each of the figures of the drawings.

As illustrated in the main figures, our invention is shown and described for two wedges which are applied to a keg-head A, although it can be applied to any other form of packing or storing vessel. The head A is divided into two sections a a, having their peripheries b beveled, as shown at b', so as to fit within the croze c' of the keg c. The space d between the head-sections a a is so constructed as to leave reverse or double tapered spaces d' d' between the edges or marginal surfaces d² d², with the greatest width in the center of the head-sections a a and contracting uniformly toward opposite sides thereof. The marginal surfaces d² d² of the sections a a are provided with grooves d³ d³, within which in the space d are adapted to fit, by means of their tongues e' e', the wedge-plates e e, which are of similar shape and 75 correspond to the double tapered spaces d' d' in the head-sections a a. The inner edges e² e² of the wedge-plates e e and the marginal surfaces d² d² on the head-sections a a, at or about the center thereof, are formed on segments of circles f' f² in order to form a hole or opening f for the reception of a stopper or bung g, which is preferably wedge-shaped, as shown. A recess h is formed in each of the wedge-plates e e for the purpose of inserting 80 and removing the wedge-plates e e when desired by means of the hands or any other suitable means, such as a hammer, &c.

The operation of our improved head for barrels, casks, &c., is as follows: In putting 90 the head A in the keg c the head-sections a a are first engaged with croze c' of the keg c by means of their peripheries b fitting therein, so as to form the spaces d' d' between them. The wedge-plates e e are then inserted from 95 the bung-hole f into the spaces d' d', with their tongues e' e' fitting within the grooves d³ d³ in the marginal surfaces d² d² of the head-sections a a, when the wedge-plates e e can be forced home by means of pressure applied to the recess h, so that their outer ends 100 fit within the croze c' of the barrel c. When

the wedge-plates *e e* are driven home, the bung-hole *f* is formed by the segments *f'* on the wedge-plates *e e* and the segments *f''* on the marginal surfaces *d² d²* of the head-sections *a a*, into which hole *f* the bung *g* can then be driven to place by any suitable means. With the shrinkages of the parts the head-sections *a a* are tightened in place by removing the bung *g* and applying pressure to the inner ends *f* of the wedge-plates *e e*, after which the hole *f* can be made larger and bung *g* can be driven back to place. In case it is desired to examine or use the contents of the keg *c* or take out the same all that is necessary is to remove the bung *g* from the hole *f*, when the contents can be examined or emptied without disturbing the other parts of the head *A*. After all or a sufficient quantity is removed the bung *g* can be placed in the hole *f* and driven home to place. When it is desired to remove the head-sections *a a* or the wedge-plates *e e* from any cause, the bung *g* can be removed from its hole *f* and the wedge-plates *e e* driven back into the bung-hole *f*, as shown in Fig. 2, from engagement with the croze *c'* in the keg *c* by means of pressure applied against the recesses *h* in the wedge-plates *e e* or against the lugs or projections *h'*, as shown in Fig. 5, when the wedge-plates *e e* will slide along the grooves *d³ d³* in the head-sections *a a* and can be removed from the spaces *d' d'* between the head-sections *a a*, after which the head-sections *a a* can be lifted from engagement with the croze *c'* in the keg *c*, when the parts composing the head *A* can be used again, if desired.

In Fig. 5 we have shown our invention as applied to a large head of a barrel, cask, &c., having within the same the parts composing our improved head *A*, which can be placed within the large head in like manner as placed within the barrel *c*.

In Fig. 6 one of the head-sections *a a* is shown as having double straight faces and the other is shown as having double tapered faces, with which wedge-plates having a tapered face only on one side are adapted to engage.

In Fig. 7 the bung-hole is placed off from the center of the head, so as to provide for a large and small wedge-plate in case it is desired to have the bung-hole and bung near the edge of the barrel for any purpose.

In Fig. 8 of the drawings our invention is shown as having one wedge-plate. In this case the bung-hole *f* is placed near the edge of the keg and the head-sections of the head only form one tapered space on one side of the bung-hole, having a straight face and a tapered face therein for the reception of a wedge-plate having a straight and a tapered face thereon. On the opposite side of the bung-hole the meeting edges of the head-sections are joined together by a tongue-and-groove joint and are held in place by a brace *i*, rigidly secured to the head-sections, which acts on a pivot to protect the edges of the

bung-hole and hold the sections together when taken out, so that the head can be used again or as a lid. A handle or bail *j* extends across the space *d* and over the wedge-plate, which acts as a spring to draw the head-sections together for the purpose of removal when the wedge-plate is removed.

In Fig. 9 the head is provided with one tapered space therein for the reception of one tapered wedge-plate therein, and the head-sections are joined together on the opposite side of the bung-hole from the tapered space by means of a dowel-pin *j'*, which acts as a pin for the head-sections. The bung-hole in this instance is formed near the edge of the keg, and the spring, handle, or bail *j* is secured on the head and extends over the tapered space therein to hold the sections together when taken out and allow it to be used as a lid, if desired. The handle or bail *j* also is used to lift the head out of engagement with the keg and is adapted to be pivoted so as to be folded down against the head.

In Figs. 10, 11, 12, and 13 our improved head is shown as applied to square, rectangular, octagonal, and oval heads, respectively, each having double wedge-plates therein, and it will be seen that the bung-hole can be placed at any point in the head and the use of single or double wedge-plates permitted, as desired, without departing from the invention.

Various modifications in the construction and design of the various parts of the head can be resorted to without departing from the spirit of the invention or sacrificing any of its advantages.

It will thus be seen that our improved head for barrels, casks, &c., is cheap and simple in its construction and operation and will not get out of order. It can be placed in position and removed at pleasure without loosening the hoops or fastenings of the barrel, keg, or cask and will not injure the walls of the opening in the barrel, keg, or cask in any manner. If for any reason it is desired to expand the head to a greater extent than it was intended to occupy, the smaller end of the wedges may be cut off and the wedges driven until the required expansion is obtained. Then a new bung-hole can be cut, which of course would be larger than the old one in order that it shall embrace the full width of the wedges in their new position. It will also be seen that in some cases by moving the wedge-plates back into the bung-hole the head will become smaller in diameter, so that it can be removed, and the wedge-plates will remain intact within the head.

What we claim as our invention, and desire to secure by Letters Patent, is—

1. In a barrel, cask, &c., the combination with the head formed in sections having an opening between them and having arcs of circles cut therein, of a wedge-plate fitting within said opening and connected with the head-section by longitudinal tongue-and-groove joints, the inner end of said wedge-plate be-

ing formed on an arc of a circle so that when the plate is driven home said arc will meet the arcs cut in the head-sections and form with the same a circular opening, and a bung driven 5 in said opening.

2. In a barrel, cask, &c., the combination with the head formed in sections having an opening between them and having arcs of circles cut therein, of wedge-plates fitting within 10 said opening and connected with the head-sections by longitudinal tongue-and-groove joints, the inner ends of said wedge-plates being formed on arcs of a circle so that when

the plates are driven home said arcs will meet arcs cut in the head-sections and form with 15 the same a circular opening and a bung driven into said opening.

In testimony whereof we, the said FRANK E. PELTON and JAMES RENWICK LOVE, have hereunto set our hands.

FRANK E. PELTON.
JAMES RENWICK LOVE.
